UNITED STATES PATENT OFFICE.

HENRY MILTON HODSON, OF SPICELAND, INDIANA.

PLANT-SETTER.

SPECIFICATION forming part of Letters Patent No. 519,712, dated May 15, 1894.

Application filed September 25, 1893. Serial No. 486,434. (No model.)

To all whom it may concern:

Be it known that I, HENRY MILTON HODSON, a citizen of the United States, residing at Spiceland, in the county of Henry and State of Indiana, have invented a new and useful Plant-Setter, of which the following is a specification.

My invention relates to improvements in machines for setting out plants; the objects in view being to provide a machine, or an attachment for a planter, that is capable of accommodating two operators employed for the purpose of alternately setting out, and supporting plants in furrows formed by the machine, during the operation of covering the plants; to so arrange the machine as to be capable of raising and lowering into and out of operative position when the machine is not in use or is being turned at the end of a row, and which will mark off for the succeeding row; and that is cheap and simple in its construction and also durable.

Various other objects and advantages of the invention will appear in the following description and the novel features thereof will be particularly pointed out in the claims.

Referring to the drawings:—Figure 1 is a perspective view of a machine embodying my invention. Fig. 2 is a vertical longitudinal sectional view. Fig. 3 is a detail of the furrow-forming runner. Fig. 4 is a similar view of the trash-clearer. Fig. 5 is a perspective view of one of the covering-blades.

Like numerals of reference indicate like parts in all the figures of the drawings.

It is my design to construct the machine in such manner as to adapt it to be applied to any ordinary planter employed on a farm and to thereby effect a saving in the machine itself in the way of framework, draft, gear-wheels, &c. If desired, however, I may construct the machine as an entirety and independent of any other machine.

In the present instance, I have illustrated the transverse axle 1 and ground-wheels 2 of an ordinary planter-frame, the same being provided with the usual draft-tongue 3 that projects in front and in rear of said axle and is rigidly secured to the latter by the usual braces, bolts, or other extraneous devices. The seat-standard 4 is supported by

the beam 3 which is widened toward its rear end and the same supports a seat 5 for the accommodation of the driver. A pair of front and rear curved and notched locking-stands 6 and 7 respectively are located upon the beam 3, and the same have fulcrumed thereon bell-crank levers 8 and 9 respectively, the said levers being provided with the usual reciprocating locking-bolts or pawls for engaging with the notches of the standards and thereby locking said levers in any of their adjustments.

The machine proper comprises a pair of main beams 10, the same being declined from front to rear and at their front ends mitered and bolted together embracing a draft-plate 11. This draft-plate 11 is perforated and is designed to be connected to the draft-bar 3 of the frame by means of a pivoting-pin 12 which passes through the draft-plate and through a pair of perforated lugs which depend from the beams. Other means of connection will of course suggest themselves. The rear ends of the beams 10 may be rounded as shown and faced with metal plates 14 designed to glide over the ground. In addition to these plates, or in place of them as desired, I may employ inverted L-shaped standards 15, swiveling in the upper ends thereof on caster-shanks 16, in which are loosely journaled caster-wheels 17. A cross-bar 18 surmounts the beams 10 and is securely bolted thereto between their ends, and horizontal seat-bars 19 are bolted to the bars 18, extend rearward therefrom above the beams 10, and are bolted to vertical standards 20 which rise from the beams 10 to which they are bolted and are provided with backs 21 for the support of the operators while seated upon the slideable seats 22. These seats 22 surmount the seat-bars, and are provided upon their under sides with keepers 23 that embrace the seat-bars and are therefore adjustable thereon.

A pair of bearing ears 24 are secured to the under sides of the beams 10 near their point of meeting, and pivoted between the bearing-ears by a pin 25 is a V-shaped trash-clearer or fender 26. Straps 27 arise from the rear terminals of this fender or clearer and are loosely connected at their upper ends as at 29 to the lower end of a connecting-rod 30 which

passes up through an opening in the beam 3, back of the locking standard 6, and is pivoted as at 31 to the arm of the bell-crank hand-lever 8.

5 In a pair of bearings 32 formed in the adjusting faces of the beams 10 there are loosely journaled the diverging bearing-arms 33 formed at the upper end of the furrow-forming runner 34. These bearing-arms are located 10 in rear of the bearing-ears 24 so that the runner 34 extends in rear of the fender or clearer 26. The runner is curved and provided at its rear end with a pair of diverging plates 35, whose upper ends are surmounted by 15 flared guards 36, whose rear ends project beyond those of the plates. A transverse brake-pin 37 passes through the plates 35 and is pivotally connected to the lower end of a sliding connecting bar 38. The upper end of 20 this bar is provided with a series of perforations 39 any one of which may be pivotally connected to the rear hand-lever 9 by a pivoting-bolt 40. Hooks 41 project from the opposite sides of the connecting-bar and engage 25 with the upper ends of short chains 42 which are connected with eyes 43 located upon the upper sides of the beams 10. By this it will be seen that through a manipulation of the hand-lever 9 the connecting-rod will serve to 30 elevate or depress the furrow-opening runner and by engaging the chains with the hooks the entire device may be elevated from the ground, which is done when the machine is traveling to or from the field of operation or 35 is in the act of turning at the end of a row.

A pair of resilient bars 43' are bolted to the cross-bar 18 between the side-bars 19, and these bars extend rearward to points near the rear ends of the beams 10 and are provided 40 with blocks 44. The under sides of these blocks are faced with metal shoes 45 whose front and rear ends are upturned so as to glide over the ground, and secured to the under sides of these shoes are diagonally set 45 covering blades 46 which follow at each side of the path of the furrow-opening plates 35.

This completes the construction of the invention and the operation thereof may be briefly described as follows:

50 The machine is surmounted by the three operators, one driving, and the other two for the purpose of setting out the plants. The fender 26 is adjusted so as to move over the surface of the ground and clear the same of all trash, clods, or other loose obstructions from the path of the runner 34. The runner is set to plant as deep as may be desired, the fender and runner being locked in their adjustments by the means heretofore described.

60 The machine moving it will be seen with the runner forms the usual furrow, and the operators seated upon the seats 22 place the plants in proper position within the furrow thus formed, the operators working alternately in 65 a manner that will be at once obvious, and also holding the plants in position until the furrow-closing blades 46 have directed the

soil against said plants, when they will be held thereby.

This completes the simple operation, and 70 it will be seen that the plants are all held in position until the soil is applied, whereby I avoid any danger of entirely covering the plants or setting them improperly, in that by the time that the operator releases them they 75 have been properly covered or set. If at any time the runner should meet with an obstruction calculated to injure the same, the brake-pin becomes fractured, and the runner is permitted to glide thereover without injury. 80

I may employ both the shoes 14 and the caster-wheels 17, or substitute the one for the other as may be desired.

I do not limit my invention to the precise details of construction herein shown and described, but hold that I may make such variations therein as shall suggest themselves during the practical operation of the machine. 85

Having described my invention, what I 90 claim is—

1. In a machine of the class described, the combination with a suitable framework, of the diverging beams, supports for the rear ends of the same, seats carried by each of the 95 beams, a lever carried by the framework, means for locking the same, a runner having its front end loosely connected to the beams and provided at its rear end with furrow-forming blades, a connecting-rod between the 100 lever and the runner for adjusting the latter, and covering-devices arranged in rear and at opposite sides of the path of the runner, substantially as specified.

2. In a machine of the class described, the 105 combination with a framework, of a pair of pivoted beams, seats carried by the beams, supports for the rear ends of the beams, a runner having furrow-forming blades pivoted between the beams, furrow-closing devices at 110 opposite sides of the runner in rear of the blades, a hand-lever carrying a locking-pawl, a locking-standard, a connecting-rod between the hand-lever and the furrow-opening runner, hooks at opposite sides of the connecting-rod, and short chains engaging the hooks 115 and secured to the diverging beams, substantially as specified.

3. In a machine of the class described, the combination with a framework having front 120 and rear locking standards, front and rear levers arranged thereon and provided with locking-paws for engaging the standards, of a pair of diverging beams loosely pivoted at their front ends to the framework in advance of the 125 levers, seats arranged upon the beams near their rear ends, supports for the beams, a V-shaped trash-clearing fender pivoted at its front end between the beams, and below the same connecting devices between the rear 130 ends of the fender and the front lever, a furrow-forming runner pivotally connected to the beams in the rear of the fender, a connecting-rod between the same and the rear lever, and

furrow-covering devices arranged in rear and at the sides of the furrow-forming runner, substantially as specified.

4. In a machine of the class described, the combination with a framework, of diverging beams pivoted at their front ends thereto, supports for the rear ends of the beams, a furrow-forming runner connected with the beams, a lever for raising and lowering the same, a pair of bars extending rearward from the beams at each side of the runner and provided upon their under sides with diagonally set blades, substantially as specified.

5. In a machine of the class described, the combination with a framework, of a pair of diverging beams pivoted thereto, a lever arranged upon the framework, connections between the same and the beams, a cross-bar arranged upon the beams, a furrow-forming runner supported by the beams and extending in rear of the cross-bar, a pair of spring bars extending from the cross-bar at each side of the furrow-forming runner, blocks secured

to the rear ends of the spring-bars, metal shoes having upturned ends arranged upon the under sides of the blocks and provided with diagonally disposed blades, substantially as specified.

6. In a machine of the class described, the combination with the framework, of the pivoted diverging beams terminating at their rear ends in runners, vertical standards rising from the beams, horizontal seat-bars, backs secured to the standards, seats arranged upon the bars and having keepers upon their under sides for engaging the bars, and furrow-opening and covering devices arranged between the seats, substantially as specified.

In testimony that I claim the foregoing as my own I have hereto affixed my signature in the presence of two witnesses.

HENRY MILTON HODSON.
